R. R. PAGE

TAILPIECE FOR BANJOS

Filed Nov. 15, 1921

UNITED STATES PATENT OFFICE.

ROBERT R. PAGE, OF NEW YORK, N. Y.

TAILPIECE FOR BANJOS.

Application filed November 15, 1921. Serial No. 515,285.

To all whom it may concern:

Be it known that I, ROBERT R. PAGE, a citizen of the United States, residing in New York, in the county of New York and State of New York, have invented certain new and useful Improvements in Tailpieces for Banjos, of which the following is a specification.

This invention relates to tail pieces for banjos and the like and has for one object 10 to provide in a device of this kind means whereby a member passes upon and equally tensions all of the strings for simultaneous-
ly raising their pitch.

Another object of the invention is to pro-
15 vide in an apparatus or device of this kind improved means for anchoring the strings on the tail piece and guard means for cov-
ering the anchoring means, but permitting the guard means to be raised for placing the
20 ends of the strings in said anchoring means.

Other objects of the invention are to im-
prove generally the simplicity and efficiency
of such devices and to provide a device or
apparatus of this kind which is durable,
25 economical to manufacture and operate and
which will not easily get out of order.

Another object of the invention is to in-
crease the tension on the bridge which im-
proves the quality of the tone and holds the
30 bridge firmly in contact with the diaphragm
and prevents the bridge from falling down
while playing.

For the accomplishment of these and
35 other objects my improved tail piece com-
prises, briefly stated, a main supporting
member formed with an anchor plate se-
cured on the banjo and provided with slot-
ted lugs receiving the ends of the strings. A
40 tension frame pivoted on said plate is con-
structed to engage and adjustably press
upon the strings between said lugs and the
banjo bridge; and a guard plate pivoted on
said frame covers said lugs and furnishes
45 convenient support for the hand while play-
ing.

Other objects of the invention will appear
as the description proceeds; and while here-
in details of the invention are described, the
invention is not limited to these, since many
50 and various changes may be made without
departing from the scope of the invention
as claimed.

In the accompanying drawing, showing
by way of example one of many possible em-
55 bodiments of the invention,

Fig. 1 is a plan of a fragment of the banjo

with my improved tail piece applied there-
to;

Fig. 2 is a side elevation of the tail piece;

60

Fig. 3 is a plan of the tail piece;

Fig. 4 is a fragmental side elevation show-
ing the tension frame out of contact with the
strings;

Fig. 5 is a side elevation showing the ten-
sioning frame pressing upon the strings to 65
raise their pitch;

Fig. 6 is a side elevation of the main sup-
porting member;

Fig. 7 is a plan of the supporting mem-
ber;

70

Fig. 8 is a side elevation of the frame and
guard plate, the latter being closed; Fig.
8a is a plan view of the guard plate removed
from the tail piece.

Fig. 9 is a side elevation of the frame and 75
guard plate, the plate being open; and

Fig. 10 is a perspective view of the guard
plate.

The improved tail piece is shown in com-
bination with a banjo having a frame or 80
shell 5, a strain rim 6, a suitably tensioned
diaphragm 7, strings 8 and a bridge 9 rest-
ing on the diaphragm.

The tail piece comprises a main support-
ing member 10 (Fig. 2) formed with an 85
upper anchor plate portion 11 engaging over
the diaphragm, an intermediate vertical por-
tion 12 having an outwardly stamped abut-
ment 13 intermediately thereon, and an out-
wardly horizontally disposed lower portion 90
14 having a horizontal slot 15 (Fig. 7)
therein. Upwardly projecting staggered
cylindrical anchoring lugs 18 riveted or oth-
erwise anchored on the top face of said plate
portion are provided at the top with narrow 95
longitudinal cuts 19 receiving knotted or
looped ends of the strings 8 and holding the
strings tensioned.

A bracket 20 (Fig. 5) bolted to said shell
below said lower portion has therein a ver-
tical bore receiving a strain bolt 21 having
100 its upper portion disposed in said slot 15
and having a head 22 (Fig. 2) and jam nut
23 engaging above and below said lower
portion 14. Lock nuts 25 and 26 on the 105
lower end of the strain bolt and engaging
said bracket 20 above and below allow ad-
justment up and down and hold said sup-
porting member 10 in place against the ten-
sion of the strings.

110 The anchor plate portion 11 is provided on
two of its corners with the upturned aper-

2
tured ears 28 (Figs. 2 and 3). The rectangular tension frame 30 is pivoted at a point on each of its side members 31 to the ears 28 for tilting movement, the forward member 32 of this frame being disposed transversely over the strings about midway between the bridge and said lugs 18, and by tilting movement of the frame being contactible with the strings for pressing downwardly thereon. The rear member 33 of the frame is slightly downwardly and rearwardly inclined and provided with a rearwardly and slightly downwardly projected lug 34 (Fig. 2) having a threaded hole therein alined with said abutment 13 and receiv- 15 ing a headed thumb bolt 35 engaging said abutment whereby when the thumb bolt is screwed in (Fig. 5) said forward member is pressed upon and equally tensions all of the strings for thereby simultaneously raising or lowering the pitch of all of them.

When preferred there may be added a guard plate 38 (Fig. 8) provided at its forward corners with downturned ears 39 pivoted to the forward corners of the tension frame, and having its rear portion 40 slightly downwardly turned to conform to the tension frame. Said rear portion 40 is provided with yieldable corner clips 41 frictionally embracing the tension frame and an intermediate cut-away portion 42 to permit the guard plate to pass the head of the tension bolt 35 when the guard plate is raised (Fig. 9) for placing the ends of the strings in said cuts 19 of the lugs. In the event of breaking a string, the clips 41 may be released and the guard plate may be swung upwardly on its pivot 39, Fig. 9, thus exposing the strings and permitting replacement of the broken string, without in the least disturbing the tension or pressure of the frame 30 upon the other strings and the while maintaining the other strings at the former desired pitch. When the new string is in place the guard plate may be returned to covering position and the new string attuned to the pitch of the other strings. The guard plate being continuous protects the hands from contact with the lugs and knotted or looped ends of the strings and furnishes a firm smooth comfortable support for the wrist during playing. It also hides the lugs and improves generally the appearance of the tail piece.

65 I claim as my invention:

1. The combination, with a banjo, of a tail piece secured on said banjo and comprising a body portion having an outstanding abutment thereon, and an anchor plate 60 provided with slotted lugs receiving the ends of the strings; upturned perforated pivot ears on the forward corners of said plate portion; a rectangular tension frame having its side members intermediately pivoted on said ears, its forward member disposed

over the strings about midway between the bridge and said lugs, and its rear member slightly offset and rearwardly inclined and provided with a rearwardly projected lug having a threaded hole therein alined with 70 said abutment; and a thumb screw in said threaded hole and engaging said abutment whereby when the thumb screw is screwed in, said forward member presses upon and equally tensions all of the strings for simultaneously raising their pitch. 75

2. The combination with a banjo having a shell, and a diaphragm and strings, of a tail piece comprising a main supporting member formed with an upper anchor plate 80 portion engaging over the diaphragm, an intermediate body portion engaging against the shell and an outwardly horizontally disposed lower portion having a slot therein; means for anchoring the strings on the anchor plate; a bracket bolted to said shell below said lower portion and having a bore therein; a strain bolt in said slot and bore having a head and jam nut engaging above and below said lower portion; and a strain 90 nut on the lower end of the strain bolt and engaging said bracket and holding said supporting member in place against the tension of the strings.

3. The combination, with a stringed musical instrument, of an anchoring member operatively secured to the body of the instrument having means for securing one end of the strings to said member; a tensioning member arranged for contact with the strings for affecting the pitch thereof; means for moving the tensioning member to tensioning position and retaining it therein; and a guard member normally covering the tensioning member and the ends of the strings and said means for securing them to the anchoring member; the guard member being movable to uncover the ends of the strings and said means for securing them to the anchoring member.

4. The combination, with a stringed musical instrument, of an anchoring member operatively secured to the body of the instrument having means for securing one end of the strings to said member; a tensioning member mounted on the anchoring member for tilting movement and when tilted contactible with the strings transversely thereof for affecting the pitch of the strings; the tensioning member having space for exposing when in tensioning position the ends of the strings and said means for securing them to the anchoring member; means for tilting the tensioning member and retaining it in tensioning position; and a guard member carried by the tensioning member; the guard member normally covering the tensioning member and the ends of the strings and said means for securing them to the anchoring member; the guard member being 120 110 100 105 115 125 130

movable to uncover the ends of the strings and said means for securing them to the anchoring member.

5. The combination, with a stringed musical instrument having a bridge, of an anchoring member operatively secured to the body of the instrument having means for securing one end of the strings to said member; a tensioning member mounted on the anchoring member for tilting movement, one end of the tensioning member when said member is tilted being contactible with the strings transversely thereof for downward pressure thereon at a point about midway between the bridge and the means for securing the strings to the anchoring member; the tensioning member having space for exposing when in tensioning position, the ends of the strings and said means for securing them to the anchoring member; means for tilting the tensioning member and retaining it in tensioning position; and a guard member pivotally mounted on the tensioning member having means for releasably gripping it thereto; the guard member normally covering the tensioning member and the ends of the strings and the means for securing them to the anchoring member and

being movable to uncover the ends of the strings and said means for securing them to the anchoring member.

6. The combination with a banjo, of a tail piece comprising an anchor plate portion secured to the banjo, means for anchoring the strings of the banjo on said plate; a tension frame pivoted on said plate having a downturned rear portion and constructed to engage and adjustably press upon the strings of the banjo; a headed tension adjusting bolt for said frame; and a guard plate provided at the forward corners with downturned ears pivoted to the forward corners of the tension frame, and having its rear edge portion slightly downwardly turned to conform to the tension frame and having yieldable corner clips embracing the tension frame and an intermediate cut-away portion to permit the guard plate to pass the head of the tension bolt when the guard plate is raised for placing the ends of the strings in said anchoring means.

ROBERT R. PAGE.
